UNITED STATES PATENT OFFICE.

HARVEY WORRALL, OF TOPEKA, KANSAS.

MUSIC SHEET AND BOOK SUPPORTER FOR PIANOS AND ORGANS.

SPECIFICATION forming part of Letters Patent No. 336,613, dated February 23, 1886.

Application filed May 27, 1885. Serial No. 166,823. (No model.)

To all whom it may concern:

Be it known that I, HARVEY WORRALL, a citizen of the United States, residing at the city of Topeka, in the county of Shawnee and 5 State of Kansas, have invented a new and useful Improvement in Music Sheet and Book Supporters for Pianos and Organs, of which the following is a specification.

The object of my invention is to prevent 10 the tearing and abrasion of the edges of music-sheets and the leaves of music-books when mounted to their place upon the piano and organ by coming in contact with the stop-strip of the book-rack when they are turned by or 15 for the performer.

My device is illustrated by the following drawings, in which Figure 1 represents the device complete in place and in working order when the book is used. Fig. 2 represents 20 a similar view when the sheet is in use. Fig. 3 shows the device alone from the face, fitted to receive and support the book; and Fig. 4 shows the opposite face of the device fitted to receive the sheet. Fig. 5 shows another substantial form of my device in so far as it is 25 designed for a book-supporter.

Similar letters represent similar parts in the several views.

The device consists substantially of two 30 boards, A, identical as to material and form, constructed of any desired material and proportions as to length, breadth, and thickness, united at one edge, as in case of the two lids of the cover of a book, by the back B, of any 35 desired breadth.

Within about an inch or so of the edge of the two lids or boards A, which rest upon the piano or organ, as is the present common custom in case of a music sheet or book, 40 a channeled ledge, C, is provided upon one side of each board A, extending nearly or quite across their respective widths. This channeled ledge may be constructed of any suitable material, and may be secured to the 45 boards in any desired manner. The width of the channel in this ledge should be sufficient to receive readily the lid of the cover

of the music-book D which is to be dropped into it. The depth of the channel should at the same time be sufficient to provide for the 50 lid a secure lodgment therein.

When my improvement is constructed as now described, and placed upon a piano or organ, where and as the sheet or book is now placed for the player, and the book is placed 55 against it, the lids alone of the box dropping into the channeled ledges C, the leaves of the book are left free to be turned backward or forward, and their lower edges are lifted quite above the stop-strip E of the book and 60 sheet rack, and so the possibility of the leaf of the book being torn by it when the leaf is turned by or for the player is entirely done away with, at the same time the greatest possible facility is afforded for turning the 65 leaf. Again, similar provision is made for the music-sheet by securing to one of the boards A upon its opposite side, near to the uniting-back B, a stiff wire, i, preferably of steel, at one end, x, and providing an eye 7c or catch, y, into which the free end of this wire may be passed, and by which it may be held down against the sheets after this sheet has been put into place against the boards A, the ledge not being required for 75 the support of the music-sheet. It is now readily seen that my device may also serve the purpose of a portfolio for either the music-sheet or for the book.

The ledge C, upon which the book rests, may 80 be plain or unchanneled; but its full purpose is best subserved when it is channeled as in the drawings.

Another substantial form of my device, in so far as it acts as a book-supporter, is supplied by two channeled strips of wood or other suitable material, of the desired length, breadth, and thickness, connected together in any suitable manner at their ends, or remaining disunited. The channel, too, may 85 be plowed out by a cutting-plane, or it may be formed by properly securing to the opposite sides of a strip of wood or other material still wider strips, and they may be 90

made to incline somewhat toward each other, so as to clasp the lids of the book when their edges are pressed into the channels.

What I claim as my invention, and desire to secure by Letters Patent, is—

A music sheet and book supporter for pianos and organs, consisting of the boards A, connected by the union B, in combination with the channeled ledge C, and the wire i,

pivoted at one end and adapted to engage in a catch at the other end, the whole constructed, combined, and operating substantially as and for the purpose hereinbefore described.

HARVEY WORRALL.
